PILLOW REST

Samuel Alexander, Hartford, Conn.

Application March 19, 1936, Serial No. 69,657

5 Claims. (Cl. 248—226)

This invention relates to pillow rests such as may be used on couches and also to a device which can be used as a guard on a child's bed to prevent a child from falling.

5 My present invention comprises an improvement over the invention covered in my pending application, Serial No. 30,319, filed July 8, 1935.

An object of my present invention is to provide a rest which can be secured in position on a 10 mattress and in such a manner that it cannot be easily displaced.

A further object, of my invention, is to provide a device of the character described which can be used as a guard for the purpose above set out.

15 As illustrated in the drawing:

Figure 1 is a perspective view illustrating my improved support.

Figure 2 is an end view of a couch illustrating the manner in which the said support is attached 20 thereto for supporting a pillow thereon.

Figure 3 is a plan view in section on line 3—3 of Figure 4.

Figure 4 is a fragmentary view, on an enlarged 25 scale, showing the construction of the clamping means.

In the form illustrated, my improved guard comprises a frame having a pair of L-shaped side members 5—5 which are joined by connecting bars 6—6. If desired, the said frame may be 30 constructed of a single piece of rod joined together, as by welding, at 7.

The clamping member consists of a pair of sleeves 8 which are mounted upon vertical posts 9 of the side members 5.

35 The said sleeves 8 are formed by a series of coils formed from the ends of parallel extensions 10 which are joined together by a clamping bar 11. Straight bar portions 12 extend upwardly from the top coils of said sleeves and may be secured in engagement with the bars 9 by means 40 of clamping washers 13 which fit around the said bars and have a notch 14 to receive the extensions 12.

In the use of my improved support, in combination 45 with a mattress, the lower extensions of the side members 5 are inserted under the mattress and the clamping member, comprising the bar 11, is forced downwardly upon said mattress by sliding the sleeves 8 on the bars 9. It will be noted that the forward portion of the bars 10 is bent slightly downwardly. This will cause the bar 11 to imbed itself firmly in the mattress and at the same time cock the coils laterally, causing 50 them to clamp unto the bars 9 and thus retain the support firmly attached to the mattress.

After the said clamping member is firmly pressed into engagement with the mattress and clamped thereon by the sleeves 8, the said sleeves are additionally clamped to the bars 9 by means of the washers 13 which are forced downwardly over the extensions 12 thus forcing the said extensions with their ends against the bars 9 and thereby clamping the same thereto to prevent upward movement of the said sleeves upon the bars.

If it is desired to use my support as a safety 10 guard for a child's bed, the said support is used in the same manner as illustrated in Figure 2, with the exception that slip covers 15 and 16 may be used over the said guard as illustrated in dotted lines in Figure 1.

15 I claim:

1. A support of the character described comprising L-shaped side members, coils forming sleeves slidable thereon, extensions on said sleeves, and means slidable on said extensions and side 20 members for securing the said sleeves by clamping said extensions to said side members, and a clamping bar member extending from said sleeves for clamping said support in position.

2. A support of the character described comprising a frame having L-shaped members, a clamping member slidable on said L-shaped members; the said clamping member comprising a 25 unitary wire structure formed to provide sleeves surrounding portions of said support, extensions 30 on said sleeves, and separate means slidable upon said extensions and side members for securing said extensions in engagement with said support to retain the said clamping member in clamped position thereon.

3. A support of the character described comprising L-shaped side members and a clamping member operating to secure a mattress upon the base of said side members, coils integral with said clamping member and slidable on said support 40 for clamping said clamping member thereto upon engagement with said mattress, and separate means comprising extensions on said coils and 45 separate members slidable upon said side members and extensions for securing said coils to said support.

4. A support of the character described comprising L-shaped side members, a clamping bar adapted to clamp the said support to a mattress, sleeves on said clamping bar slidable on said side 50 members, extensions on said sleeves normally spaced from said L-shaped side members and securing means slidable upon said side members over the ends of said extensions for securing the 55

same to said side members when the said securing members are moved over said extensions.

5. A support comprising a frame having parallel upright members, a U-shaped member slideable on said upright members; the said U-shaped member comprising a unitary wire structure formed to provide sleeves surrounding portions

of said upright members, extensions on said sleeves, and separate means slideable on said extensions and upright members for securing said extensions to said upright members to retain the said U-shaped member in clamped position 5 thereon.

SAMUEL ALEXANDER.
